UNITED STATES PATENT OFFICE.

MAUDE SIEGEL, OF NEW YORK, N. Y., ASSIGNOR TO FRANKLIN SIMON & CO., INC., OF NEW YORK, N. Y., A CORPORATION OF NEW YORK.

DESIGN FOR A DRESS.

Application filed February 25, 1927. Serial No. 20,898. Term of patent 3½ years.

To all whom it may concern:

Be it known that I, MAUDE SIEGEL, a citizen of the United States, and a resident of the city of New York, borough of Manhattan, in the county and State of New York, have invented a new, original, and ornamental Design for Dress, of which the following is a specification, reference being had to the accompanying drawing, forming part thereof, wherein the dress is distinguished by an ornamental arrangement of trimming bands extending around the neck and from the neck centrally at the front down to the bottom of the blouse with a circumferentially arranged band at the bottom and a belt above the bottom agreeing in general appearance with the ornamental bands.

Figure 1 is a perspective view of a dress, showing my new design, the same being illustrated on a figure.

Figure 2 is an enlarged fragmentary rear view of the lower part of one of the sleeves shown in Figure 1.

Figure 3 is an enlarged fragmentary view of a portion of the belt shown in Figure 1, said portion illustrating the appearance of the buckle and belt ornamentation.

I claim:

The ornamental design for a dress, substantially as shown and described.

MAUDE SIEGEL.
